UNITED STATES PATENT OFFICE.

THOMAS ARTHUR, OF BANGOR, PENNSYLVANIA, ASSIGNOR TO HIMSELF
AND ROBERT J. NAGLE, OF SAME PLACE.

COMBINED AIR-EXHAUSTER AND WATER-ELEVATOR.

SPECIFICATION forming part of Letters Patent No. 330,366, dated November 17, 1885.

Application filed March 31, 1885. Serial No. 160,787. (No model.)

To all whom it may concern:

Be it known that I, THOMAS ARTHUR, of Bangor, in the county of Northampton and State of Pennsylvania, have invented certain new and useful Improvements in a Combined Air-Exhauster and Water-Elevator, of which the following is a full, clear, and exact description.

Reference is to be had to the accompanying drawings, forming part of this specification, and which is a sectional side elevation of my improvement.

The object of this invention is to provide a simple and reliable mechanism for elevating water or drawing air from mines and other places.

The invention relates to a combined air-exhauster and water-elevator constructed with a conical tube inserted in a water-pipe and connected by an air-pipe with the upper part of the short arm of an elevator, the lower end of the said short arm being provided with a water-seal, and the upper end of the long arm of the elevator being extended downward past the end of the air-pipe, and its lower part being provided with an air-inlet, whereby water and air can be readily withdrawn from mines and other places, as will be hereinafter described and claimed.

A is a pipe open at both ends, and connected at its upper end with a water-supply by a spout or other suitable means. Within the upper end of the pipe A, and not in contact with it, is suspended a conical tube, B, with its smaller end downward. The larger upper end of the conical tube B is connected with one end of an air-pipe, C. The other end of the air-pipe C is connected with the top part of the pipe D.

E is an inverted-L-shaped tube, the upper end of which is secured air and water tight in the upper end of the pipe D, and is extended a little below the end of the air-pipe C. The lower end of the tube E extends down to the place from which the water or air is to be withdrawn.

In one side of the lower part of the pipe D E is secured a small air-inlet tube or nipple, F. With the lower end of the pipe D is con-

nected a short elbow-pipe, G, to form a water-seal for the said lower end, to prevent air from entering the said pipe D from its lower end.

The construction at the lower end of the pipe D is immaterial so long as air is prevented from entering the said end and water allowed to flow out freely.

With this construction, as the water flows into the pipe A past the conical tube B its tendency to form a vacuum in front of the said tube B draws the air from the said tube B and from the pipe C and the pipe and tube D E connected with it. When the lower-end of the pipe D is closed so as not to admit air, or when the said pipe contains so much water that its weight equals the suction-power of the exhauster A B, and the lower end of the tube E is immersed in water with the nipple F above the surface of the said water, water and air will flow through the said tube E into the pipe D, where they will separate, the water flowing out through the said pipe D and the air flowing through the pipe C and the conical tube B into the pipe A, so that as long as the said pipe A is supplied with water and the end of the tube E is immersed in water there will be a continuous outflow of water at the siphon G at the lower end of the pipe D. In case there be no water at the lower end of the tube E, air will be drawn up through the said tube E so long as the pipe A is kept supplied with water.

Having thus fully described my invention, I claim as new and desire to secure by Letters Patent—

1. A combined air-exhauster and water-elevator constructed substantially as herein shown and described, and consisting of the conical tube B, inserted in the water-pipe A and connected by the air-pipe C with the upper part of the pipe D, the lower end of the said pipe being provided with a water-seal, and the upper end of the tube E being extended downward past the air-pipe C, and its lower part being provided with an air-inlet, F, as set forth.

2. In a combined air-exhauster and water-elevator, the combination, with the upper part

of the pipe D, having its lower end provided with a water-seal, and having the upper end of the tube E extended into the upper part of the said pipe, and provided near its lower end 5 with an air-inlet, F, of the pipe C, the conical tube B, and the water-pipe A, substantially as herein shown and described, whereby wa-

ter and air can be readily withdrawn from mines and other places, as set forth.

THOMAS ARTHUR.
